UNITED STATES PATENT OFFICE.

WOLDEMAR REINHOLD HEINITZ, OF CHEMNITZ, GERMANY, ASSIGNOR TO THE NATIONAL CASH REGISTER COMPANY, OF DAYTON, OHIO, A CORPORATION OF OHIO, (INCORPORATED IN 1906.)

CASH-REGISTER.

1,186,575.

Specification of Letters Patent. Patented June 13, 1916.

Application filed June 8, 1912. Serial No. 702,419.

To all whom it may concern:

Be it known that I, WOLDEMAR REINHOLD HEINITZ, a citizen of the Kingdom of Saxony, residing at Chemnitz, Germany, have 5 invented certain new and useful Improvements in Cash-Registers, of which I declare the following to be a full, clear, and exact description.

This invention relates to accounting machines and the principal object thereof is to provide an improved form of mechanism for listing items and the totals thereof.

Another object of this invention is to provide an improved mechanism having a variable movement whereby an impression may be taken from independent sets of type carriers, such as item and total type carriers one of which sets has its printing position in advance of the other set of type 20 carriers.

Another object of this invention is to provide means for with-drawing one of the plurality of sets of type carriers from printing position and holding said set of type 25 carriers out of printing position whereby an impression may be taken from the remaining sets of type carriers, the latter sets of type carriers being of smaller diameter than the withdrawn set of type carriers.

Another object of this invention is to provide a plurality of independent sets of manipulative devices with interlocking mechanism between said devices whereby 35 when the manipulative devices of one set is operated, the manipulative devices of the other sets are rendered inoperative, with additional means operative at will for rendering inoperative either set of said manipulative devices.

A further object of this invention is to provide an item and total listing machine with a consecutive numbering device, which is rendered operative as an accompaniment 45 to the listing of totals.

With these and incidental objects in view, the invention consists in certain novel features of construction and combination of parts, the essential elements of which are 50 set forth in appended claims, and a preferred form of embodiment of which is hereinafter described with reference to the drawings which accompany and form part of this specification.

Of said drawings, Figure 1 is a transverse 55 sectional view through a machine of well known type to which this invention has been shown applied. Fig. 2 is an end elevation partly in section of the improved recording mechanism. Fig. 3 is a horizontal sectional 60 view taken through the machine just below the key board. Fig. 4 is a detail sectional view taken adjacent to one of the amount banks of keys. Fig. 5 is a plan view of the mechanism coöperating with the amount keys 65 and showing two of the banks of keys in section. Fig. 6 is a detail sectional view taken adjacent to one of the banks of number or special keys. Fig. 7 is a plan view 70 of the mechanism coöperating with the number keys and showing two banks of said keys in section. Fig. 8 is a detail view of the total manipulative device and mechanism controlled thereby for restoring the total type carriers to normal or zero position. 75 Fig. 9 is a detail view of the mechanism for operating the consecutive numbering device.

Described in general terms the improved machine comprises a plurality of banks of 80 amount keys which control item and total printing type carriers, and a plurality of banks of number keys which control type carriers for listing numbers or other special characters as an accompaniment to the listing of totals. When a key of either set is operated, the keys of the remaining set are rendered inoperative. Mechanism is also provided for temporarily rendering either set of keys inoperative. The item and total 85 type carriers are of different diameter and means is provided for imparting a variable throw to an impression mechanism so as to list upon a record strip the items or totals as may be desired. In the listing of totals, 90 the item type carriers, which are of larger diameter than the total type carriers, are positioned so as not to interfere with the taking of the totals. Mechanism is provided for restoring the total type carriers to normal 95 position as an incident to the listing of the total and also for operating a consecutive numbering device. Both the item and total sets of type carriers are provided with 100 duplicate characters so as to record the items and totals thereof upon an inserted slip, as well as upon a permanent record strip.

For the sake of illustration the above listed improvements have been shown applied to a machine of a well known type and which is fully shown and described in Letters Patent of the United States Nos. 875,075 issued December 31, 1907 and 1,134,195 issued April 6, 1915 on inventions of Woldemar Reinhold Heinitz, but it is to be understood that these improvements are not to be limited to this particular type of machine, but may with equal facility be applied to other well known types of machines now upon the market.

As previously stated, the machine is provided with a plurality of banks of amount keys 1 and as shown in Fig. 1, the keys of each bank are arranged to be latched in their depressed position by a detent 2. The keys of each bank control the differential 15 adjustments of a segmental actuator 3, which is driven by a driving member 4 pivotally mounted adjacent to said actuator upon a series of sleeves 5, which surround a transverse shaft 6, the latter being suitably supported by the side frames 7 of the machine. The driving members 4 are connected by a cross rod 8, the ends of which are supported by arms 9 pivotally mounted upon the sleeves 5. Projecting upwardly 20 from each of the arms 9 at its pivotal point, is a segmental rack plate 10, which co-operates with a similar plate 11 secured to the main rotary shaft 12. The shaft 12 is rotated in the direction of the arrow, Fig. 1, 25 by a suitable crank handle or other operating mechanism not shown, and through the segments 11 move the driving members in an anti-clock direction. After the segments 11 pass out of mesh with the segments 10, the driving members 4 are returned to their normal position by cams 13 which engage with intermediate device 14 pivoted upon a cross rod 15. These intermediate devices 14 bear upon lugs 16 projecting from the driving member 4 so that when the cams 13 engage with the intermediate members 14 and move them in a clockwise direction, they will in turn move the driving members in a similar direction. 30 The mechanism is suitably arranged to effect re-engagement of the segments 10 and 11 at near the end of the rotation of the shaft 12, but just how this is accomplished need not be explained here, as it forms no part of the present invention. The differential segments 3 are arranged to be left in their adjusted position at the end of each operation of the machine and upon the beginning of the succeeding operation the cross bar or 35 rod 8 engages with the adjusted actuators and restores said actuators slightly beyond their normal or zero position and as the driving members are returned to their normal position, the actuating segments are free to move back to their zero position, in

which position they are arrested by flip pawls 17, carried by said actuating segments, coming into contact with off-sets 18 of the zero keys. If any of the keys other than the zero keys are depressed in the amount banks, the said zero keys would be projected outwardly, thereby carrying the off-sets 18 out of the path of movement of the pawl 17, while the off-sets 18 of the depressed keys would be positioned so as to arrest the segments 3 by the pawl 17 coming into contact with said off-sets. It is to be understood that there is a suitable clutch mechanism between each driving element 4 and its actuating segment 3 so that the said actuating segments are moved in a clockwise direction by the driving members 4 until segments 3 or members 4 are unclutched by the depressed keys. This clutch mechanism is fully shown in the aforementioned Heinitz patent and as it forms no part of the present invention it is thought that no further description thereof need be given.

The differential movement of the actuating segments 3 is conveyed through gears 19, 20 and 21 to the front and back indicators 22 and 23 respectively. Directly beneath each amount bank of keys 1 is located a disk 24 which is secured to the main rotary shaft 12. Each of these disks 24 is provided with a series of laterally movable actuating teeth 25 and a transfer tooth 26. These teeth are normally out of the same vertical plane as accumulative pinions 27, 100 but are arranged to be projected into the same plane as said pinions by the keys 1, the number of teeth so projected being determined by the key depressed. That is, if the 5 key is depressed five teeth 25, co-operating with that particular bank of keys will be projected into the same plane as the co-operating pinion so that upon the rotation of the disk 24, the pinion 27 will be advanced five steps. After actuating pinion 27, the teeth 25 are returned to their normal position by a suitable cross bar not shown. Previous to their restoration, these teeth are arranged to engage with a pinion 28, which through intermediate gear 29 and pinion 30 rotate elements 31 of a grand accumulator having numerals engraved thereon as shown in Fig. 3, so that the amounts accumulated thereon may be read from the front of the machine, while the pinions 27 115 of a sub-accumulator are suitably connected to accumulating type carriers for printing the amount on the sub-accumulator as hereinafter more fully described.

When one of the pinions or elements 27 of the sub-accumulator passes from nine to zero position, it will force rearwardly a pawl 32, Fig. 1, which pawl controls the projecting of the transfer tooth 26 of the next higher disk 24 in operative relation with its 120

pinion 27 so as to advance the latter one step, after which the transfer tooth returns to its normal inoperative position. Projecting from each one of the disks 24 is a stud 33 which will restore the displaced pawls 32 to their normal position upon the succeeding operation of the machine before the teeth 25 engage with either of the pinions 27 or 28. Coöperating with each of the pawls 32 is a spring pressed pawl 34 which tends to hold each pawl 32 in its normal or adjusted position. The pawls 32 are pivotally mounted upon the transverse rod 15, while the pawls 34 are mounted upon a rod 35. No transfer mechanism has been shown for the elements 31 of the grand accumulator, but it is to be understood said elements may be provided with any of the well known forms of transfer mechanism.

The number keys 36, Fig. 6, have, coöperating therewith, actuating segments 3, which are driven by members 4 in the same manner as the segments 3 which coöperate with amount banks of keys. These segments 3 coöperating with the number keys drive indicators appearing at the front and back of the machine in identically the same manner as the amount segments. As it is intended that these number keys should simply record and indicate, no disks 24 are provided for actuating the sub and grand accumulators.

In the particular embodiment of the invention herein shown, the number keys control the type carriers for printing suitable identifying characters as an accompaniment to the listing of totals and in order to prevent the operation of any of the amount keys, suitable interlocking mechanism is provided between the amount and number keys, which will now be described.

Coöperating with each bank of amount keys 1, as shown in Fig. 4, is a cam plate 37 which is arranged to be moved downwardly upon the depression of any of the amount keys from one to nine by the pin 38 of the depressed key engaging with the incline 39 of the plate 37. At its rearward end the plate is suitably attached to a cross rod 39 supported at the extreme lower end of arms 40, which in turn are fastened at the upper end to a rock shaft 41. This downward movement of the plate 37 will cause the rock shaft 41 to move in a clock-wise direction, which will cause plates 42, Fig. 6, coöperating with the different banks of number keys to move downwardly thereby bringing the upper surfaces of said plates 42 into position under the key pins 43 of the number keys 36 so as to prevent the depression of the latter keys. The locking plates 42, coöperating with the number keys 36 have inclines 44 running in an opposite direction from the inclines 39 of the plates 37. From this it will be seen that when one of the number keys 36, is first depressed the plate 42, co-

operating therewith will be moved rearwardly and through cross rod 39 carry the plates 37, coöperating with the amount banks of keys so as to bring the upper locking surface of said plates beneath key pins 38 and thereby prevent the depression of any of the amount keys. It will be noted that the slots formed by the inclines 39 and 44 of the plates 37 and 42 respectively have radial walls so as to permit the actuation of a key in another bank of the set to which the depressed key belongs.

Fast to the rock shaft 41 is an upwardly extending arm 45 which carries at its upper end a plate 46 having inscribed thereupon the words "amount" and "number" Fig. 7, which words are brought beneath the opening 47 formed in the cabinet 48 of the machine so as to indicate the set to which the operated key belongs. The plate 46 is provided with notches 49 into which the end of a lock bolt 50 is arranged to be projected when it is desired to lock for any length of time any section of the key board. The plate 46 is held in its normal position, as shown in Fig. 7, by a coil spring 51, Fig. 6, the ends of which are connected to the cross rod 39 and to a pin 52 projecting from one of the frames of the machine.

Coöperating with each bank of number keys 36, is a second plate 53 having inclines 54 with which the key pins 43 are arranged to coöperate. Upon the depression of one of the number keys, the plate 54, coöperating therewith will be moved downwardly and an extension 55 of said plate will engage with an arm 56 secured to shaft 57 and rock said shaft in a clock-wise direction. As shown in Fig. 7, there is one of the arms 56 for each of the plates 53. The shaft 57 has secured thereto, directly beneath the amount banks of keys, a plate 58 having a hook portion 59, which hook portion, when a number key is depressed, is in position to engage with the flip pawls 17 of the segments 3, coöperating with the amount banks of keys when said segments are moved to their abnormal or beyond zero positions by the cross rod 8 as previously described. The object of latching these segments 3 coöperating with the amount banks of keys in their abnormal position is to permit the taking of a total as hereinafter more fully described.

In the specific embodiment of the recording mechanism, about to be described, there are shown independent sets of type carriers for listing items and the totals thereof, with a single device for taking impressions from both sets of type carriers. The position of the type carriers in listing items, is slightly in advance of the printing position occupied by the total type carriers, which necessitates a variably movable mechanism in order to take impression from both the item and total type carriers. As

an accompaniment to the listing or printing of totals, suitable identifying characters are also listed as well as a consecutive number.

Three of the differentially adjusted segments 3 cooperating with the amount banks of keys have attached thereto at their pivotal points one end of yokes 60, Figs. 1 and 3, the other ends of said yokes being secured to several of the nested sleeves 61.

16 The fourth amount segment 3 is rigidly connected to the innermost sleeve 61. The sleeves at their outer ends have secured thereto arms 62, Fig. 2. These arms 62 are connected by links 63 to plates 64 carrying two sets of type 65 and 66 for listing items upon a record strip 67 and an inserted slip 68 respectively, said plates 64 being cut away between the sets. The total type carriers 69, Figs. 2 and 3 are interspersed 20 among the item type carriers 64 and are connected by nested sleeves 70 to pinions 71. These pinions 71 are connected through intermediate gears 72 to pinions 73 fastened to outer ends of sleeves 74, which at their 25 inner ends carry the pinions 27 of the sub-accumulator heretofore described. The three differentially adjusted segments 3 cooperating with the number keys are shown at the right of Fig. 3. Two of these segments at their pivotal points are connected to yokes 75 while the other one of said segments is secured to the inner end of one of the series of nested sleeves 5, the other ends of the yokes 75 being connected to the inner 30 ends of the remaining sleeves 5. All of the sleeves 5 are supported upon the shaft 6, which in turn is suitably supported by the side frames of the machine. The extreme outer ends of the sleeves 5 connected to the 35 number segments 3 have secured thereto arms 78 similar to the arms 62, and these arms 78 are connected by links 79 to number type carriers 80, which links are similar to the links 63, shown in Fig. 2. The number 40 type carriers 80 are provided with duplicate sets of type and these carriers, as well as the item carriers 64 and total carriers 69 are supported upon a shaft 82, which in turn is suitably supported by the frame work of 45 the machine. The purpose of providing the yokes 60 and 75, instead of connecting the segments 3, directly to the sleeves 5 is for the purpose of bringing the type carriers in their proper position so that the impressions taken therefrom may be correctly read.

From Figs. 2 and 3, it will be seen that the item type carriers 64 are of greater diameter than either the total type carriers 69 or the number type carriers 80 and consequently in order to take impression from the total and number type carriers, it is necessary to impart to the impression mechanism a greater throw in the listing of totals than is necessary in the listing of items.

50 The mechanism for imparting this variable throw to the impression mechanism will now be described. A slide 83 is guided upon one of the side frames of the machine by studs 84 which extend through elongated slots 85 formed in said slide. This slide is 55 provided with a platen 86 for taking an impression from the type carriers upon the record strip 67 and also with the platen 87 for taking impressions upon the inserted slip 68. This slide 83 has connected thereto 60 one end of a link 88, the other end of which link is provided with a pin 89 that normally rests in the upper end of an elongated slot 90 formed in the lower end of a lever 91, which is pivoted at 92 to one of the side frames. Approximately at its center this lever 91 is provided with a roller 93, which plays in a cam groove 94 formed upon a disk 95 secured to a shaft 96. This shaft at its right hand end, Fig. 3, is provided with 65 a gear 97, which meshes with a similar gear 98 secured to the main rotary shaft 12 and which receives a complete rotation upon each operation of the machine. The pitch 70 size of the gears 97 and 98 are shown in Fig. 2 of the drawings. The shape of the cam groove 94 in the disk 95, is such that with the parts in position, as shown in Fig. 2, this groove will move the lever 91 first in an anti-clockwise direction, which will, 75 through the link 88, carry the slide 83 in a forward direction to take an impression upon the inserted slip 68 from the item type 80 66, which have previously been adjusted. Upon the continued rotation of the 85 disk 95, the slide 83 will be moved rearwardly to carry the platen 86 in contact with the type 65 so as to list upon the strip 67, an item corresponding to the amount 90 keys depressed, after which the slide 83 is 100 restored to the position as shown in said Fig. 2. This operation is repeated for every item to be listed, it being understood that the record strip 67 is fed by suitable mechanism not shown between the impressions made thereon, while the slip 68 may be manually adjusted at each operation of the machine to present a new portion to the type carriers, or suitable mechanism may be provided for the purpose thereby making 105 the manual adjustment of the slip unnecessary. Such mechanism need not be shown and described in this application, however, as it forms no part of the present 110 invention.

When the total of the entered items is to be listed, a total manipulative device 99, which is the upper key in the left hand bank of number keys, is depressed. This key is connected by a link 100 to an arm 101 115 secured to a shaft 102, Figs. 2 and 3, which extends through the machine. At its left hand end this shaft is provided with a forwardly extending arm 103 to which is connected, by a link 104, the link 88. From 120

this it will be seen that upon the depression of the total key, the shaft 102 will be rocked in a clockwise direction and through arm 103 and link 104, rock the link 88 in a similar direction carrying the pin 89 to the lower end of the slot 90 formed in the lever 91. With the pin 89 in the lower end of the slot 90, it will be obvious that upon the movement of the lever 91, the slide 103 will be given a greater movement than when the pin 89 is in position shown in Fig. 2. This excess movement is sufficient to bring the platens 86 and 87 into contact with the total type carriers 69 and the number type carriers 80. It may be well to state here that the total manipulative device 99 controls the latching plate 58, as shown in Figs. 1, 4 and 6 in the same manner as previously described in connection with the number keys and that said total manipulative device may be operated with said number keys or independently thereof. It will be recalled that by positioning of the latching plate 58, to engage with the flip pawls 17 of the segments 3, coöperating with the amount banks of keys, the said segments will be latched in their abnormal position, and these segments being connected to the item type carriers will consequently rotate said type carriers beyond zero position to bring their cut away portions adjacent the platens so as not to interfere with the taking of impressions by the platens 86 and 87 from the total type carriers 69 and the number type carriers 80. After the total is listed and the total manipulative device released, the latch plate 58 is restored to its normal position by a spring 105, which permits the segments 3 coöperating with the amount banks of keys to return to their normal or zero positions where they are arrested by the zero keys. It is to be understood that a suitable inking ribbon, not shown, may be interposed between the platens and type carriers so that the impressions on the record strip and the inserted slip may more easily be read. After the total is recorded, the accumulating pinions 27 and total type carriers 69 connected thereto, are restored to their normal or zero position by the following described mechanism.

Suitably connected to each of the pinions 27 of the sub-accumulator is a heart-shaped cam 106, Figs. 1 and 3, with which engage pawls 107, secured to a rock shaft 108. This rock shaft at its left hand end, Fig. 8, has secured thereto an upwardly extending arm 109, the upper end of which is provided with an elongated slot 110 into which extends a pin 111, projecting from a slide 112, the latter being guided upon one of the side frames of the machine by a pin 113 and the shaft 102, which extend through elongated slots 114 and 115 respectively. While items 113 are being listed a roller 116, projecting from

the arm 109, Fig. 8, plays in a concentric groove 117 formed in the disk 95 upon the opposite side of said disk from the previously described groove 94. When the total key is depressed, the shaft 102 as previously described is rocked in a clockwise direction and a pin 118, projecting from an arm 119, secured to said shaft 102, will cam a slide 112 forwardly by said pin 118, engaging with an incline extension 120 of the slot 115. This forward movement of the slide 112 will move the arm 109 in a clockwise direction, carrying the roller 116, projecting from said arm into a cam groove 121 formed in the disk 95. The shape of the groove 121, is such that near the very end of rotation of the shaft 96, carrying said disk 95, the arm 96 will be rocked further in a clockwise direction, which will cause the pawls 107, projecting from the shaft 108, to engage with the heart-shaped cams 106 and restore said cams with the pinions 27 of the sub-accumulator and the total type carriers 69 to normal or zero position. This restoration of the pinions 27 of the sub-accumulator occurs after the transfer teeth, carried by the disks 24, pass beyond said pinions so that in case the pawls 32 are actuated in the restoration of the pinions 27, no harm will be done, as said pawls 32 are restored at the beginning of the succeeding operation of the machine.

A consecutive numbering device, comprising the three type wheels 122 of the same diameter as the total type wheels 69 and the number type wheels 80 are suitably mounted upon the shaft 82. A multi-prong pawl 123, Figs. 3 and 9, carried at the upper end by a lever 124, engages with the type wheels, so as to feed said wheels when the lever 124 is rocked a proper distance. This lever, at its lower end, has an elongated slot 125, in which projects a pin 126, extending from the lower rearward end of a centrally pivoted lever 127. The upper end of this lever 127 is provided with an elongated slot 128 into which extends a pin 129, projecting from the member carrying platen 86. In the listing of items, the platen 86 is not moved a sufficient distance to carry the pawl 123 in engagement with the next tooth of the units type wheel 122 of the consecutive numbering device, but upon the printing of totals the platen 86 is given a movement, which is sufficient to carry the pawl 123 in engagement with the next tooth by the intermediate mechanism just described and fully illustrated in Fig. 6. As the platen is restored to normal position the units type carrier will be advanced one step.

From the above it will be seen that by printing the consecutive number as an accompaniment to the printing of the totals the latter will be easily distinguished from the listed items, but it is to be understood

that applicant is not limited to this manner of distinguishing the totals from the items and by some of the claims it is intended to cover other means obvious to those skilled in the art.

While independent sets of type carriers have been described for listing items and the totals thereof, it is to be understood that applicant is not to be limited to this precise construction, but in some of the claims wherein it is recited that the consecutive numbering device is operated as an accompaniment to the listing of totals, it is intended to cover constructions employing a single set of type carriers for listing items and the totals as well as the construction herein shown.

A machine embodying the above described improvements may be put to various uses, but it is particularly suited in tax offices for listing the various classes of taxes such as "personal" and "real" and the total thereof upon the tax receipt, also upon the record strip which is stored in the machine. When thus used, the numbered type carriers are used for the purpose of identifying the person for whom the taxes are paid, while the consecutive numbering device is used for listing the number of people for whom the taxes are paid. With the grand accumulator, the total amount of taxes paid, may be ascertained at any time desired.

While the form of mechanism herein shown and described is admirably adapted to fulfil the objects primarily stated it is to be understood that it is not intended to confine the invention to the one form of embodiment herein shown and described as it is susceptible of embodiment in various forms all coming within the scope of the claims which follow.

What is claimed is:

1. In a machine of the class described, the combination with independent sets of type carriers for printing items and the totals thereof, the printing position of one of said sets being in advance of the other set, of an impression mechanism, means for giving to said mechanism a variable movement for the purpose of recording upon a record strip from either set of type carriers, and means for withdrawing the advanced set of type carriers when it is desired to record upon the record strip from the other set of type carriers.

2. In a machine of the class described, the combination with independent sets of type carriers for printing items and the totals thereof, the printing position of the items set of type carriers being in advance of the total set of type carriers, of an operating mechanism, means normally actuated thereby for taking an impression from the item type carriers, a total manipulative device, and means controlled thereby for causing

the operating mechanism to impart a greater movement to the impression means so as to take an impression from the total set of type carriers.

3. In a machine of the class described, the combination with independent sets of type carriers for printing items and the total thereof, the printing position of the item set being in advance of the total set of type carriers of an operating mechanism, means normally actuated thereby for taking an impression from the item type carriers, a total key, and means controlled by said key for permitting the taking of an impression from the total type carriers and then restoring said total type carriers to zero position.

4. In a machine of the class described, the combination with type carriers for listing items and the total thereof, of a consecutive numbering device, and means for printing the consecutive number as an accompaniment to the listing of the total only.

5. In a machine of the class described, the combination with independent sets of type carriers for listing items and the total thereof, of a consecutive numbering device, and means for printing the consecutive number as an accompaniment to the listing of the total only.

6. In a machine of the class described, the combination with type carriers for listing items and the total thereof, of a numbering device, and means for operating said device as an incident to the listing of the total only.

7. In a machine of the class described, the combination with independent sets of type carriers for listing items and the total thereof, of a numbering device, and means for operating said device as an incident to the listing of the total only.

8. In a machine of the class described, the combination with independent sets of type carriers for listing items and the total thereof, of a single set of keys controlling the said type carriers, a third set of type carriers for listing numbers as an accompaniment to the listing of totals, a second set of keys controlling the number type carriers, and interlocking mechanism between the two sets of keys.

9. In a machine of the class described, the combination with independent sets of type carriers for listing items and totals thereof, of a single set of keys controlling the said type carriers, a third set of type carriers for listing numbers as an accompaniment to the listing of totals, a second set of keys controlling the number type carriers, and means controlled by the second set of keys for preventing the listing of items.

10. In a machine of the class described, the combination with independent sets of type carriers for listing items and totals thereof, the printing position of the item

- set being in advance of the total set of type carriers, of a single set of keys controlling said type carriers, a third set of type carriers for listing numbers as an accompaniment to the listing of totals, a second set of keys controlling the number type carriers, an operating mechanism, means controlled thereby for withdrawing the item type carriers from printing position at each operation of said mechanism, means controlled by the number keys for holding the item type carriers in withdrawn position and a total key controlling the listing of numbers and the totals.
11. In a machine of the class described, the combination with type carriers, of mechanism for taking impressions therefrom, means for variably moving said impression mechanism in opposite directions for the purpose of listing items and the total thereof upon a record strip and an inserted slip, and means for distinguishing the total from the items listed upon both the strip and the slip.
12. In a machine of the class described, the combination with type carriers, of mechanism for taking impressions therefrom, means for variably moving said mechanism in opposite directions for the purpose of listing items and the total thereof upon a record strip and an inserted slip, and means for listing a character in juxtaposition to the total listed upon the record strip and the slip and as an incident to the listing of the total for the purpose described.
13. In a machine of the class described, the combination with a plurality of sets of type carriers, each set being of different diameter and bearing duplicate type, of mechanism for taking impressions therefrom, means for variably moving said mechanism in opposite directions for the purpose of listing items and the total thereof upon a record strip and an inserted slip, and means for listing a number in juxtaposition to the total listed upon the record strip and the
- slip and as an incident to the listing of the total for the purpose described.
14. In a machine of the class described, the combination with consecutive number type carriers, of operating devices therefor, an element having different extents of movement, and connections whereby the operating devices are moved at each movement of said element, but operative the type carriers only when the element moves through its greatest extent of movement.
15. In a machine of the class described, the combination with type carriers arranged to list items and the total thereof, of a platen having a variable movement to record either items or totals on a record strip, consecutive number type carriers, operating devices therefor, and connections through which the variable movement of the platen is transmitted to the operating devices whereby to operate the consecutive number type carriers as an incident to printing totals only.
16. In a machine of the class described, the combination with a movable platen having an invariable starting point, of independent sets of type carriers for listing items and the total thereof, the type at the printing position of the item carriers being never the starting point of the platen than those of the total carriers, means for giving the platen a positive variable movement whereby to take an impression on a record strip from either set of carriers, a consecutive number printer, operating devices therefor, and connections through which the variable movement of the platen is imparted to the operating devices whereby to operate the consecutive numbering device as an incident to printing totals only.
- In testimony whereof I affix my signature in the presence of two witnesses.
- WOLDEMAR REINHOLD HEINZT. [L. S.]
- (Witnesses):
- SIDNEY RICH,
M. BENNDALE.
